UNITED STATES PATENT OFFICE

126,501

DESIGN FOR A DRESS

Rose Bersano, Brooklyn, N. Y.

Application March 1, 1941, Serial No. 99,274

Term of patent 3½ years

To all whom it may concern:

Be it known that I, Rose Bersano, a citizen of the United States, residing in Brooklyn, New York city, in the county of Kings and State of New York, have invented a new, original, and ornamental Design for a Dress, of which the following is a specification, reference being had to the accompanying drawing, forming part thereof.

I claim:

The ornamental design for a dress, substantially as shown.

ROSE BERSANO.
